METHOD OF AND APPARATUS FOR TRUING OUT-OF-ROUND CAN BODIES

John Drygulski, Hillside, N. J., assignor to American Can Company, New York, N. Y., a corporation of New Jersey

Application November 28, 1950, Serial No. 197,999

4 Claims. (Cl. 153—32)

The present invention relates to a method of and apparatus for truing containers or can bodies and has particular reference to rounding-up cylindrical can bodies which have been deformed into an out-of-round condition during handling. This is a continuation-in-part of my application Serial No. 784,921 filed November 8, 1947, now Patent No. 2,558,741, issued July 3, 1951.

In the handling of cylindrical cans preparatory to filling them with a product or otherwise treating them, the open end of the cans sometimes become bent into an oval or otherwise out-of-round condition and thus prevents proper fitting and sealing of the covers onto the cans after filling. This is partly due to the fact that the open end of the can is not as strong and as rigid as its closed bottom, because the bottom of the can is reinforced by the end closure member which is secured thereto. Such out-of-round cans, when encountered in a batch of round cans being fed automatically into the customary filling and sealing machines, are the source of considerable trouble since they jam and sometimes cause damage to the machines when the covers cannot be properly fitted into place and secured to the cans.

The present invention contemplates overcoming these difficulties by the provision of a method of and apparatus for reforming out-of-round cans into a properly rounded or trued condition preparatory to filling and sealing.

An object of the invention is the provision of a method of and apparatus for truing cans wherein the cans are rotated by pressure applied to the rigid portion of the cans while other pressure is applied to the distorted yieldable portion of the cans to reform the distorted portion into a truly rounded condition so that the covers of the cans will properly fit into place on the cans after filling so as to insure proper sealing of the cans.

Another object is the provision of such a method of and apparatus for truing cans wherein out-of-round cans having radially projecting end seams at their closed ends and radially projecting flanges formed on their opposite open ends may be effectively reformed into a true rounded condition for application of their covers thereto.

Another object is the provision of such a method of and apparatus for truing cans wherein simplicity of operations in the method and similar characteristics in the structure of the apparatus, insure economical and highly efficient results under high speed rates of production.

Numerous other objects and advantages of the invention will be apparent as it is better understood from the following description, which taken in connection with the accompanying drawings, discloses a preferred embodiment thereof.

Referring to the drawings:

Figure 1 is a side elevation of an apparatus embodying the instant invention, with parts broken away;

Fig. 2 is a vertical section taken substantially along the line 2—2 in Fig. 1, with parts broken away;

Figs. 3 and 4 are enlarged sectional details of the apparatus illustrated in Fig. 1 and showing a can in place,

2

Fig. 3 showing the can before being reformed into a true rounded condition, and Fig. 4 showing the can after being reformed;

Figs. 5 and 6 are sectional details of modified forms 5 of apparatus disclosed in Fig. 1, the views showing an out-of-round can in place in the apparatus for truing, with parts broken away;

Fig. 7 is a side elevation of a further modified form of the invention, with parts broken away; and

10 Fig. 8 is a vertical section taken substantially along the line 8—8 in Fig. 7.

As a preferred embodiment of the instant invention the drawings illustrate a method of and apparatus for truing an out-of-round cylindrical sheet metal container or can A comprising a tubular body B (Figs. 3 and 4) having a rigid true round bottom C secured thereto at one end in a suitable radially projecting end seam D and having its opposite yieldable end open and formed with a radially projecting flange E for the reception of a cover after the container is filled with a product.

The method of truing such an out-of-round can comprises, as the first step, the rotation of the can on its longitudinal axis by pressure exerted against the outer periphery of its rigid true round radially projecting end seam D. During this rotation of the can its longitudinal axis is maintained in a predetermined position parallel with the path of travel of the can. This is for the purpose of rotating the out-of-round body of the can on the longitudinal axis of the entire can. While the can is so rotated other pressure is exerted diametrically against its out-of-round body wall only and at a place between the end seam and the flange of the can. This diametrical pressure against the out-of-round body wall squeezes the yieldable open end of the body along its major diametrical axis, slightly beyond its elastic limit and thereby causes the squeezed body wall to take a permanent set substantially equal to the true diameter of the can.

In the drawings Figs. 1, 2, 3 and 4 illustrate a preferred form of apparatus for carrying out the above 40 method steps of truing out-of-round can bodies. This apparatus includes a pair of spaced and parallel wheels which constitute a driving wheel 11 and a truing wheel 12, which are formed on a hub 13 mounted on a driving shaft 14 journaled in bearings 15 carried in a pair of 45 spaced and parallel upright frame members 16 which extend up from a base plate 17. The radius of the truing wheel 12 is greater than the radius of the driving wheel 11, by an amount substantially equal to the radial projection of the end seam D beyond the can body B. This 50 difference in radii of the wheels 11, 12 provides between them a stepped relation which compensates for the difference between the outside diameter of the end seam D and the outside diameter of the body B and thus provides for contact with the seam and the out-of-round portion of the body while the longitudinal axis of the can remains in a horizontal plane.

On their outer peripheries the wheels 11, 12 preferably 55 carry a resilient tread 18 made of rubber, leather, or other suitable material for frictionally engaging against a can A to be rotated and trued. This tread may be sunk into a groove 19 in the circumference of the wheels 11, 12 as shown in the drawings, if desired. The wheels 11, 12 are continuously rotated, through the shaft 14, in any suitable manner in a counterclockwise direction as 60 viewed in Fig. 1.

Adjacent the outer periphery of the wheels 11, 12 the apparatus is provided with a curved stationary track 21 comprising a pair of stepped parallel track sections which constitute a driving track section 22 and a truing track section 23. This track 21 is bolted to the base plate 17. The driving and truing track sections 22, 23 are disposed in radial alignment with the peripheries of the driving and

truing wheels 11, 12 and extend around the wheels in parallelism therewith for substantially one half of their circumference.

The truing face of the truing track section 23 is spaced inwardly from the driving face of the driving track section 22 by an amount substantially equal to the radial projection of the end seam D beyond the can body B. This difference in height or spacing of the faces of the track sections 22, 23 provides between them a stepped relation which compensates for the difference between the outside diameter of the end seam D and the outside diameter of the body B and thus provides for contact with the seam and the body while the longitudinal axis of the can remains in a horizontal plane. The respective width and spacing of these track sections are such as to provide engagement of the driving track section 22 only with the end seam D of the can A, and engagement of the truing track section 23 only with the out-of-round portion of the body of the can at a place between the can end seam D and the flange E, preferably adjacent the flange but not engaging the flange.

The space between the curved inner face of the driving track section 22 and the outer circumference of the resilient tread 18 on the driving wheel 11 is substantially equal to the outer diameter of the end seam D of a can A to be trued so that the end seam of a can introduced between the wheel and its track section 22 will have continuous, uniform frictional driving engagement with the wheel and the track section. The space between the curved inner face of the truing track section 23 and the outer circumference of the resilient tread 18 on the truing wheel 12 is substantially equal to the true outer diameter of the body B of a can A to be trued, this space being concentric with the space between the wheel 11 and its track section 22, the two spaces having coincident curved center lines. Hence a true round body will readily pass between the truing wheel 12 and the truing track section 23 without reformation, but an out-of-round body will be forced between these truing elements by rotation of the can on its end seam and thus the body will be squeezed along its major diametrical axis, into true round body formation.

At its upper end, the curved track 21 is secured to the upright frame members 16 and projects outwardly at an angle beyond these members and thus provides an upper inlet chute member 25 for the introduction of cans A into the apparatus. The chute is completed by a spaced and parallel lower chute member 26 which is disposed in spaced and parallel relation with the upper chute member 25 and which is secured to this member and to the frame member 16. Adjacent the lower ends of the frame members 16, the track 21 terminates in an outwardly and downwardly inclined track 28 for the discharge of the trued cans from the apparatus.

In operation, a continuous procession of cans A, including normally round cans and any out-of-round cans that may be mingled with them, the latter being marked X in Fig. 1, are introduced from any suitable source of supply, into the apparatus by way of the inlet chute members 25, 26. The cans roll down the inclined chutes on their sides and enter into the space between the driving and truing wheels 11, 12 and their co-operating driving and truing track sections 22, 23 with the end seam D of the cans entering between the driving wheel 11 and its track section 22. The resilient tread 18 on the driving wheel 11 frictionally engages against the end seam D of an incoming can and thus presses the seam into frictional engagement with the driving track section 22 (see Figs. 3 and 4).

Hence as the driving wheel 11 rotates, it also rotates the can and rolls it along the driving track section with the longitudinal axis of the can in a substantially horizontal plane parallel with the axes of the driving and truing wheels and parallel with the track sections. The driving wheel 11 and its driving track section 22 thus rotate and roll the entire can on its longitudinal axis, as a sep-

arate and independent function of the machine and through this driving action rotates and rolls the body of the can through the space between the truing wheel 12 and its co-operating truing track section 23 (see Fig. 4).

During the rotation of the bodies B of the cans A through the truing space between the truing wheel 12 and the truing track section 23, the major diametrical axis of the body of an out-of-round can X is squeezed preferably adjacent the body flange E between the truing wheel and the truing track section to such an extent that the metal of the out-of-round body passes its elastic limit and thereby acquires a permanent set. In this manner, an out-of-round can body as it traverses the truing track section 22 while being rotated is reformed or returned to a substantially true diameter or original shape and is thus in a condition for the reception of its product and a cover. This condition obtains when the can reaches the terminal end of the track 21 and the can thereupon rolls down the discharge track 28 to any suitable place of deposit.

During this travel through the apparatus the cans A are confined against endwise displacement, by guide bars 29 which are disposed at opposite ends of the cans and extend adjacent the path of travel of the cans through the apparatus. These bars are welded or otherwise secured to bracket blocks 30 which are bolted to the sides of the track 21 and the frame 16 at spaced intervals along the lengths of the bars.

Fig. 5 of the drawings illustrates a modified form of the apparatus in which the driving and truing wheels 11, 12 of the preferred form are constructed as an integral single wheel 35 mounted on the drive shaft 14. The outer surface of the wheel 35 is formed with a pair of concentric stepped faces which constitute a driving face 37 and a truing face 38. The radius of the truing face 38 is greater than the radius of the driving face 37 by an amount substantially equal to the radial projection of the end seam D beyond the can body B. This difference in radii of the faces 37, 38 provides between them a stepped relation which compensates for the difference between the outside diameter of the end seam D and the outside diameter of the can body B and thus provides for contact with the seam and the out-of-round portion of the body while the longitudinal axis of the can remains in a horizontal plane.

This two faced, stepped wheel 35 co-operates with the track 21. The driving and the truing track sections 22, 23 of the track are disposed in radial alignment with the peripheries of the driving face 37 and the truing face 38 of the wheel and extend around the wheel in parallelism therewith as in the preferred form of the apparatus. The width of the wheel faces 37, 38 are such as to provide engagement of the driving face 37 only with the end seam D of the can A and engagement of the truing face 38 only with the out-of-round portion of the body of the can at a place between the can end seam D and the flange E, preferably adjacent the flange but not engaging the flange.

The space between the driving face 37 of the wheel 35 and the driving track section 22 of the track 21 is substantially equal to the outer diameter of the end seam D of a can A to be trued so that both the driving face and the driving track section will frictionally engage the outer periphery of the can end seam D of a can introduced between these wheel face and track section elements. In a similar manner the space between the truing face 38 of the wheel 35 and the truing track section 23 of the track 21 is substantially equal to the true outer diameter of the body B of a can A to be trued, this space being concentric with the space between the driving face 37 and the driving track section 22, the two spaces having coincident curved center lines, so as to compress only the out-of-round portion of the body along its major diametrical axis while the longitudinal axis of the can is maintained in a predetermined position.

In this modified form of the apparatus, the operation of truing an out-of-round can body is substantially the same as that effected by the preferred form, the entire

can being rotated on its longitudinal axis independently and separately from the truing apparatus by frictional engagement of the driving face 37 and the driving track section 22 with the outer periphery of the end seam D of the can. The rotation of the can rolls the can body B between the truing face 38 and the truing track section 23 and thus reforms the out-of-round can body to a true cylindrical shape as explained hereinbefore in connection with the preferred form of the apparatus.

A further modification of both the track 21 and the wheel 35 is shown in Fig. 6. In this form of apparatus the track sections 22, 23 of the track 21 are separated by a clearance recess 41 and the driving and the truing faces 37, 38 are separated by a clearance recess 42. In this construction of the apparatus, the width and location of the two stepped faces of the integral wheel 35 and the width and location of the two stepped track sections 22, 23 of the integral track 21 may be limited to engagement with selected portions of the can to perform different functions without interfering in any manner with other portions of the can.

Figs. 7 and 8 disclose a further modified form of apparatus in which the cans A to be trued are rolled along a straight line path of travel. In this form of the apparatus the entire can A is rotated or rolled on its longitudinal axis by engagement with the outer periphery of its end seam D, by an endless narrow driving belt 45 and a driving rail 46 which extend for nearly the full length of the apparatus.

The driving belt 45 is disposed in a horizontal position and operates over a pair of spaced driving pulleys 43 located one at each end of the apparatus. The pulleys are mounted on a pair of spaced and parallel shafts 49 journaled in bearings 50 formed in upright brackets 51 secured to an elongated frame 52 which constitutes the main frame of the apparatus. One of the shafts 49 serves as a main drive shaft and may be rotated in any suitable manner. A pressure or back-up bar 54 is disposed adjacent and above the lower run of the driving belt 45 to back-up this run of the belt. The bar at its ends is supported on brackets 55 secured to the upright brackets 51.

The driving rail 46 is disposed opposite and in vertical alignment with the driving belt 45 and extends in spaced and parallel relation to the lower run of the belt. This rail is bolted to the top of the frame 52. The rail is spaced away from the driving belt 45 a distance substantially equal to the outside diameter of the end seam D of a can A to be trued so that the end seam of a can introduced between the belt and the rail will have continuous, uniform, frictional driving engagement with both of these elements.

The truing of the out-of-round portion of the can A is effected by a truing belt 61 and a truing rail 62. The truing belt 61 is disposed in laterally spaced relation to the driving belt 45 and operates over a pair of spaced pulleys 63 mounted on the shafts 49 adjacent the driving pulleys 43. The radii of the truing pulleys 63 are greater than the radii of the driving pulleys 43 by an amount substantially equal to the radial projection of the end seam D beyond the can body. This difference in radii of the pulleys 43, 63, with the same thickness of belt on each pulley, provides between the belts a radially stepped relation which compensates for the difference between the outside diameter of the end seam D and the outside diameter of the body B and thus provides for contact with the seam and the out-of-round portion of the body while the longitudinal axis of the entire can remains in a horizontal plane.

A pressure or back-up bar 65 is disposed adjacent and above the lower run of the truing belt 63 to back-up this run of the belt. The bar at its ends is supported on brackets 66 secured to the upright brackets 51.

The truing rail 62 is disposed opposite and in vertical alignment with the truing belt 63 and extends in spaced and parallel relation to the lower run of the belt. This

rail is also disposed in spaced and parallel relation to the driving rail 46 and like the rail 46 is bolted to the top of the frame 52. The space between the upper or truing face of the truing rail 62 and the truing belt 63 is substantially equal to the true outer diameter of the body B of a can A to be trued, this space being horizontally aligned with the space between the driving belt 45 and the driving rail 46, the two spaces having coincident horizontally disposed center lines, so as to compress only the out-of-round portion of the body along its major axis while the longitudinal axis of the can is maintained in a horizontal plane.

The truing face of the truing rail 62 is higher than the driving face of the driving rail 46 by an amount substantially equal to the radial projection of the end seam D beyond the can body B. This difference in height of the rails 46, 62 provides between them a stepped relation which compensates for the difference between the outside diameter of the end seam D and the outside diameter of the body B and thus provides for contact with the seam and the body while the longitudinal axis of the can remains in a horizontal plane.

The width of the driving and the truing rails 46, 62 is such as to provide engagement of the driving rail 46 only with the end seam D of the can A and engagement of the truing rail 62 only with the out-of-round portion of the body of the can at a place between the can end seam and the flange E, preferably adjacent the flange but not engaging the flange.

At the entrance end of the apparatus, the left as viewed in Fig. 7, the driving and the truing rails 46, 62 preferably are formed with inclined portions 68 to permit incoming cans to roll into position between the driving and the truing belts 45, 61 and the cooperating rails 46, 62. Similarly at the discharge end of the apparatus the rails 46, 62 slope downwardly and outwardly in discharge portions 69 to carry the trued cans to any suitable place of deposit.

During their passage through the apparatus, the cans A are confined against endwise displacement, by guide bars 71 which are disposed at opposite ends of the cans and extend adjacent the path of travel of the cans. These bars preferably are welded or otherwise secured to bracket blocks 72 which are secured to the upright brackets 51.

In this modified form of the apparatus, the operation of truing an out-of-round can body is substantially the same as that effected by the preferred form, except that the can is rolled along a straight line path of travel. It should be understood that in this modified form of the invention the belts 45, 61 could be combined in a single stepped wide belt having an outer face corresponding to the face of the wheels 35 shown in Figs. 5 and 6 and in a similar manner the tracks 46, 62 could be made integral as shown in Figs. 5 and 6.

In all of these forms of the apparatus and in the steps of the method, it should be understood that the same principle of operation obtains, the principle of driving or rotating a can by contact with a known true round portion of the can, which in practice is the end seam D, and through this rotation, maintaining the longitudinal axis of the can in a predetermined position while guiding the out-of-round portion of the can between spaced truing elements which reform and return the out-of-round portion of the can to its true original round shape.

It is thought that the invention and many of its attendant advantages will be understood from the foregoing description, and it will be apparent that various changes may be made in the form, construction, and arrangement of parts of the apparatus mentioned herein and in the steps and their order of accomplishment of the method described herein, without departing from the spirit and scope of the invention or sacrificing all of its material

advantages, the apparatus and method hereinbefore described being merely a preferred embodiment thereof.

I claim:

1. In an apparatus for truing an out-of-round body wall of an open end substantially cylindrical container having a radially projecting end seam at a closed end of the container and a radially projecting flange at its opposite open end, the combination of a pair of movable spaced parallel belt members having driving faces respectively engageable with the projecting container end seam and with an axially spaced outer peripheral body wall portion of the out-of-round container between said end seam and said flange, means for positively driving one of said belt members, a pair of pressure bars for respectively holding said belt members in engagement with the aforesaid axially spaced portions of said container, and a track member disposed adjacent said belt members in spaced relation thereto, a portion of said track member holding the projecting end seam of said container against said driving face of one belt member to effect rotation of said container about its longitudinal axis, another laterally spaced and substantially parallel portion of said track member being mounted to project towards said container body wall a distance greater than said first mentioned track member, said another track member portion being spaced from the driving face of the second belt member a distance substantially equal to the true diameter of the container body for cooperation with said end seam engaging belt member to tangentially engage the container body wall for exerting a diametrical pressure against the out-of-round wall of said rotated body to reform said wall into true cylindrical container formation, said reforming diametrical pressure being exerted against the container body wall solely at a locality spaced axially inwardly of the container open end.

2. In an apparatus for truing an out-of-round body wall of an open end substantially cylindrical container having a radially projecting end seam at a closed end thereof and a radially projecting flange at its opposite open end, the combination of a track member and a movable member spaced from said track member, said track member comprising an end seam engaging section and a parallel body truing section spaced laterally therefrom a distance substantially the height of a container body, said body truing track section projecting toward said movable member a distance greater than said end seam engaging track section, said movable member comprising a rolling means cooperating with said seam engaging track section to frictionally rotate the container on its longitudinal axis while passing therebetween and a rotatable body truing means disposed in laterally spaced parallel relation to said rolling means a distance substantially the height of a container body, said rotatable body truing means projecting toward said body truing track section in a direction transversely of an interposed container a distance greater than said rolling means, said rotatable body truing means and said body truing track section cooperating with each other to exert a diametrically opposed pressure radially inwardly against the interposed body wall portion of an out-of-round container solely at a locality spaced axially inwardly of the container open

end to reform such body wall portion into true cylindrical configuration.

3. A method of truing the body walls of substantially cylindrical light weight sheet metal containers each having an out-of-round flexible body wall adjacent its open flanged end and having a circular bottom secured to and closing its opposite end in a rigid end seam, said method comprising advancing and simultaneously axially rotating said containers by applying frictional container rotating pressure directly against said rigid end seams, and truing the flexible out-of-round body walls of the advancing and rotating containers adjacent their open flanged ends by exerting variable external pressure against diametrically opposed flexible wall portions of the containers solely at a locality between their open flanged ends and their rigid end seams, said variable external pressure being sufficient to bend the out-of-round body wall portions radially inwardly to effect a permanent true cylindrical shape of said body wall portions when said pressure is released.

4. In an apparatus for truing an out-of-round body wall of a substantially cylindrical container having a rigid radially projecting end seam at a closed end thereof and a radially projecting flange at its opposite relatively flexible open end, the combination of a fixed arcuate track member and a rotatable cylindrical container rolling and truing member disposed in concentric relation thereto, said track member including a container end seam engaging portion and an integrally formed container body truing portion spaced laterally therefrom a distance substantially the height of a container body, said body truing track portion projecting radially toward said rotatable member a distance greater than the projection theretowards of said end seam engaging track portion, said rotatable member including a rolling portion cooperating with said seam engaging track portion to frictionally rotate the container on its longitudinal axis while passing therebetween, said rotatable member further including an integrally formed body truing portion spaced laterally from said rolling portion thereof a distance substantially the height of said container body, said rotatable member body truing portion projecting toward said track member and transversely of an interposed container a distance greater than the projection of said rolling portion towards said track member, said rotatable member body truing portion and said body truing track member portion cooperating to exert a diametrically opposed pressure radially inwardly against the interposed body wall portion of an out-of-round container solely at a locality spaced axially inwardly of the container open end to reform such body wall portion into true cylindrical configuration.
